Fig. 9.

A technical line drawing of a mechanical assembly. It features a central vertical rod with a slot. A horizontal bar with a slot is positioned above the vertical rod. A diagonal rod connects the top of the vertical rod to the horizontal bar. A small circular component is attached to the vertical rod near the top. The drawing is annotated with numbers: 24 at the top left, 70 and 48 on the left side, 49 on the far left, 50 at the bottom left, 52 and 51 on the right side, 56 at the bottom right, 54 and 53 at the bottom center, and 38 at the bottom right. A small number 25 is also present near the bottom left.

UNITED STATES PATENT OFFICE.

ELMORE D. CUMMINGS, OF WASHINGTON, DISTRICT OF COLUMBIA.

RAILWAY SEARCHLIGHT TOWER.

1,409,834.

Specification of Letters Patent. Patented Mar. 14, 1922.

Application filed February 20, 1919. Serial No. 278,310.

(FILED UNDER THE ACT OF MARCH 3, 1883, 22 STAT. L., 625.)

To all whom it may concern:

Be it known that I, ELMORE D. CUMMINGS, a citizen of the United States, and a resident of Washington, District of Columbia, have invented an Improvement in Railway Searchlight Towers, of which the following is a specification.

The invention described herein may be used by the Government, or any of its officers or employees in prosecution of work for the Government, or by any other person in the United States, without payment of any royalty thereon.

The subject of this invention is a railway searchlight tower designed for use on the seacoast, though adapted for employment in any locality in which a searchlight may be advantageously operated.

The invention aims to provide a searchlight tower, which may be transported from place to place, and which may be lowered when not in use and when being transported.

The main object of the invention is the provision of a searchlight platform which will remain in parallelism with the tower base or car floor for all positions of the tower and means for assuring such parallel motion of the searchlight platform.

Another object of the invention is the provision of means for locking the platform against movement when the tower is in elevated position, and of automatically released means for holding the locking means in unlocked position when the tower is to be lowered.

A still further object of the invention is the provision of means for permitting the operator ready access to the platform.

It is also among the objects of the invention to provide means for supporting the tower against lateral oscillation or swing when in elevated position.

With these and other objects in view, my invention consists in certain novel details of construction, combination and arrangement of parts, to be more specifically set forth and claimed.

In the accompanying drawings in which

corresponding parts are indicated by similar reference numerals:—

Fig. 1 is a view in side elevation of the assembled device, the tower shown lowered;

Fig. 2 is a plan view of the same, a portion shown in section;

Fig. 3 is a view in side elevation showing the tower raised and the trap door closed;

Fig. 4 is a view in front elevation showing the tower elevated, the trap door open, and a portion sectioned on the line IV—IV, of Fig. 3;

Fig. 5 is an enlarged detail view in side elevation of the base end of the equalizer and the tower raising mechanism parts in section;

Fig. 6 is an enlarged detail view of the upper end of the equalizer;

Fig. 7 is a perspective of the rope clamp;

Fig. 8 is a schematic view showing the action of the equalizer;

Fig. 9 is an enlarged fragmentary view in elevation of the platform, and the platform lock;

Fig. 10 is a detail plan view taken on the line X—X of Fig. 9.

Fig. 11 is a detail plan view, partly in section, of the holding means for the platform latch handle;

Fig. 12 is a detail view in elevation of the limit plate for the platform latch;

Fig. 13 is a detail view in elevation of the catch;

Fig. 14 is a perspective of a holding plate for a platform latch operating rod;

Fig. 15 is a plan view of the trap door with its operating cranks and link, a fragment of the platform being shown;

Fig. 16 is a side elevation of the same, the position of the trap door when open indicated in dotted lines; and

Fig. 17 is a sectional view taken on the line XVII—XVII of Fig. 3.

Referring to the drawings, a flat car indicated generally by reference numeral 10, is provided as a transportable support for the tower and this car is mounted on the respective front and rear trucks 11, and

11', adapted for engagement with the rails 12 of a railway track.

The truck 11 is designed to carry a motor (not shown) by means of which the car may 5 be propelled along the track. A cab 13 is provided at the forward end of the car for the convenience of the operator of the car, and this cab is provided with a doorway to permit ingress and egress to and from 10 the cab respectively, the doorway being closed by a door 14.

In the cab 13, a suitable operating lever 15 is located to permit control of the motor by which the car is driven and a hand wheel 15 16 is provided for operating the brakes of the car.

While the structure herein shown and described would be for a car operated by electric power, it is to be understood that 20 any suitable and convenient form of motive power may be employed.

Standards 17, 17 are secured to and rise from the floor of the car 10, at the sides thereof and adjacent the forward end. 25 Bearing blocks 18 are mounted on the upper ends of the standards 17 and serve as journaling means for the horizontal shaft 19, which extends transversely of the car and the ends of which project laterally beyond 30 the standards. The shaft 19 is encircled by retaining collars 20, 20 which abut against the inner faces of the journaling blocks 18 and are clamped in position on the shaft by means of set screws 21; the purpose of the 35 collars being to prevent rectilinear motion of the shaft.

The tower, indicated generally by the reference numeral 22, is mounted for swinging movement on the extending ends of the shaft 40 19, hubs 23 being secured to side plates of the tower for the purpose of receiving the ends of the shaft to provide a pivotal connection between the tower and the shaft. The tower is preferably of skeleton construction and comprises corner uprights 24 which are connected and braced by the cross braces 25, the braces being joined to the corner uprights by gusset plates 26. The 45 uprights and cross braces are preferably formed of angle bars as herein shown, though any convenient form of structural material may be used.

The tower merges at its upper end, into a yoke like formation, the pair of uprights 24 at each side of the tower converging upwardly to form the prongs of the yoke. For the purpose of reinforcing this upper portion of the tower, angle bars 27 may be secured longitudinally of the uprights 24, as 50 seen most clearly in Figs. 1, 2, 3 and 4, and arcuate angle bars 28 are secured to the corner uprights 24 and the cross braces 25 at the bottom of the yoke for the purpose of further strengthening the yoke. Plates 60 29 are secured to the converged upper ends

of the corner uprights 24 and those plates are formed with hubs 30, which form journaling means for trunnions 31 carried by the hangers 32 of a platform 33. The platform 33 is provided with a rail 34, positioned about its periphery, which serves to protect the operator of the search light and prevent his accidentally stepping from the 70 platform.

A searchlight base 35 is mounted on the 75 platform 33 and carries the supporting arms 36 in the upper ends of which the trunnions 37 of lamp 38 are journalled.

In order that the platform 33 may be maintained in parallelism with the floor of 80 the car 10 for all positions of the tower 22, an equalizer wheel 39 is rigidly secured on the trunnion 31 at one side of the platform and the wheel is apertured to receive suitable fastening, by which it is fastened to 85 the hanger 32. The wheel 39 is grooved to receive a rope 40, which is trained over the wheel, and which is clamped to the wheel by means of suitable rope clamps 41. The flights of the rope 40 are led from the wheel 90 39, longitudinally of the tower and pass through guides 42 and 43 which are secured to convenient cross braces 25. A second equalizer wheel 44, of the same diameter as the wheel 39, is mounted on an extending 95 end of the shaft 19, between the standards 17 and the side plate of the tower, and over this wheel the rope 40 is trained. Turn buckles 45, 45 may be provided in the flights of the rope 40 for the purpose of 100 properly tensioning the rope. Clamps 46 embrace the rim of the wheel 44 and serve to clamp the rope 40 firmly in place in the groove of this wheel. To retain the wheel 44 against rotation, arms 47 are bolted or 105 otherwise secured to the wheel at each side of the center and the depending ends of these arms rest upon the legs of the standard 17.

While in the foregoing description the 110 equalizer is described as having a rope or cable 40, it is to be understood that the flights between the equalizer wheels may be of rods suitably connected to the cable sections which pass over the wheels. This is 115 especially desired in tall towers where the long cable is liable to stretch or give unduly.

For the purpose of locking the platform against movement when the tower is in elevated position, a latch 48 is provided and 120 this latch has extending laterally therefrom, and positioned between its ends, a pivoting pin 49, which is journalled in a bearing 50 secured to a cross brace 25 of the tower. The forward end of the latch 48 is tapered 125 to provide an inclined edge 51 and adjacent this edge a notch 52 is formed in the latch. A catch 53 is bolted to a hanger 32 and an adjustment shim 54 is interposed between the catch and the hanger 32 for the purpose 130

of adjusting the catch to proper position. The catch 53 is so placed that the inclined edge 51 of the latch will ride over its upper end, as the platform swings into position, thereby raising the latch to bring the notch 52 into alignment with the catch.

When the tower is to be lowered it is desirable and necessary that the latch be detained in unlatched position so that the platform will be free to swing. For this purpose a rod 55 has its lower end pivotally connected at 56 to the latch 48, and this rod is slideable through an aperture formed in an angle plate 58 which is connected to a corner upright 24. The upper end of the rod 55 is bent to form a laterally extending hand grip 59 below which, when in raised position, a wing 60, which is hinged to the angle plate 58, may be swung. When this wing is swung to the position just described, it retains the handle in its elevated position and holds the latch disengaged from the catch 53 until the tower has swung to near horizontal position, when the plate will fall through gravity and release the rod to free the latch to operative position.

For the purpose of retaining the plate in rod holding position so that it will not automatically release, a pin 59' may be provided which is passed through an aperture in the hand grip 59, and the extending end of which overlies the edge of the plate, as seen most clearly in Figure 9.

The rear end of the latch 48 is bifurcated to straddle the upper end of a rod 61, the rod and bifurcated end being apertured to receive a pivoting pin 62. The rod 61 extends longitudinally of the tower, preferably at that side of the tower remote from the side at which the rope 40 is located, and is guided through guide plate 63, secured to the frame work of the tower. A turnbuckle 64 connects the lower end, 65, of the rod 61 with the upper end thereof, the turnbuckle serving to regulate the length of the rod. The lower end, 65, of the rod is bent to form a hand grip or handle 66 and the rod, at this end, is slideable through the slot 67 formed in the upper extending flange of a channel plate 68, which plate is secured to the frame work of the tower adjacent its base. The lower extending flange of the channel plate 68 is of less depth than the upper flange and has formed therein a notch 69, which is in vertical alinement with the slot 67 of the upper flange.

From the foregoing it will be seen that, when the rod 65 is drawn to the outer end of the slot 67, the handle 66 may be drawn downwardly past the outer edge of the lower flange and the rod slid into the notch 69. By referring to Fig. 14, it will be apparent that this will retain the rod in its lowermost position and, consequently, hold the latch disengaged from the catch 53. This retaining

means is also constructed so that it will automatically release under the force of gravity when the tower has been lowered to horizontal position. This mechanism is provided to permit the latch to be operated from the bottom of the tower whenever the same may be necessary.

To furnish means for limiting the movement of the latch 48, a plate 70 is secured to the corner upright 24 beside which the latch swings and the edge of this plate extends inwardly toward the latch. The extending edge of the plate is cut out to provide the upper and lower projections 71 against which the latch will alternately strike in its oscillations.

A short angle bar 72 is secured to the frame work of the tower, adjacent the latch 48, and extends for a short distance forwardly of the tower, or in a direction opposite that of the latch. The inwardly extending flange of the angle bar 72 is formed to provide an angular portion 73, which is adapted to engage a bumper plate 74 for the purpose of stopping or limiting the swing of the platform 33. The bumper plate 74 is bolted to the hanger 32 and an adjustment shin 75 is interposed between the bumper plate and the hanger for the purpose of properly positioning the plate to contact with the inwardly projecting portion 73.

The platform 33 is provided with an opening located at one corner thereof and a trap-door 76 is provided for normally closing this opening. Hinged members 77 are connected to the trap-door and to the frame work of the platform, as seen most clearly in Figs. 15 and 16, and a shaft 78 is passed through the apertures of the hinge members; the shaft being journaled in the hinge members 100 which are connected to the frame work of the platform, while the hinge members which are secured to the trap-door 76 are rigidly connected to the shaft 78. A spacing collar 77' encircles the shaft 78 and 105 is positioned between a hinged member secured to the trap-door and a member secured to the platform for the purpose of retaining the door in proper position to close the opening. On that end of the shaft 78, which extends beyond the corner of the platform, a crank 78' is rigidly secured. The crank 78' is tapped to receive a threaded extension 79 which serves to adjust the length of the crank. The outer end of the extension 79 110 is apertured and straddled by the bifurcated end of a link 80, which link has pivotal connection with the extension 79.

A shaft 81 is journaled in the frame work of the platform 33 and extends transversely 125 of the trap-door adjacent its outer edge. One end of the shaft 81 extends beyond the side of the platform and has rigidly secured thereon a crank 82 which has pivotal connection with the other bifurcated end of the 130

4
connecting link 80. The upper ends of the side bars 83 of an extension ladder are secured to the shaft 81, and spaced apart rungs 84 have their ends connected to the side bars 83. The extension ladder is positioned beneath the trap-door 76 and is held in elevated position when the trap-door is closed, as seen most clearly in Fig. 16, and, when drawn to lowered position, through the shaft 81, cranks 82 and 78', link and shaft 78; causes the trap-door to swing to opened position.

An angle arm 85 is secured to the trap-door 76 and a counter-weight 86, bolted or otherwise fastened to the upstanding member of this arm, serves to render the opening of the trap-door comparatively easy.

The lower ends of the side bars 83 of the extension ladder rest, when the extension is in lowered position, against angle plates 87 which are carried by the upper ends of the side bars 88 of a ladder having the spaced apart rungs 89 suitably secured between the side bars. The ladder is connected to the frame-work of the tower through brackets 90 and is provided to permit the attendant to ascend the tower for the purpose of operating the light.

In order that the tower may be raised and lowered, suitable mechanism is provided, which, as herein shown, consists of segmental racks 91, 91, secured at each side of the tower at its base and meshing with pinions 92, fast on the ends of a horizontal shaft 93, which extends transversely of the tower support and is journaled in bearings 94 secured to the standards 17. A worm gear support and housing 95 is secured to the floor of the car 10, midway between the standards 17, and serves to house a worm wheel 96 which is mounted on the shaft 93. The worm wheel 96 meshes with a worm 97 rigid on a horizontal shaft 98, which shaft extends for a short distance longitudinally of the car 10 and has its rearward end journaled in the worm thrust bearings 99, while its forward end is journaled in a bearing 100 secured on a standard 101 which rises from the floor of the car 10. The forward extending end of the shaft 98 has secured thereon a crank 102 by which the shaft may be rotated to actuate the gearing to raise or lower the tower.

Secured to each side of the tower, at the base thereof, are pairs of spaced apart, laterally extending ears 103 which are adapted to receive therebetween the hinge members 104, which members are connected to rectangular frames 105. The ears 103 are apertured to receive pintles by which the frames are hingedly connected to the tower.

Counter-weights, preferably in the form of sections or blocks 106, are bound in place on the frames 105 by means of through

bolts 107, as seen most clearly in Fig. 17. Certain of the blocks are apertured to permit the passage therethrough of the shafts 108 of jack screws, and these shafts are threaded to engage the internally threaded bores of blocks 109 which are carried by the frames 105.

Hand wheels 110 are provided on the upper ends of the shafts 108 through which the jack-screws may be manually operated. The lower extending end of each shaft 108 is hemispherical in formation to engage a socket formed in a foot 111. The foot 111 is held in place on the end of the shaft by means of a retaining collar 112 which encircles the shaft and is bound to the foot in any convenient and well known manner.

Apertured plates or lugs 113, 113 are secured to the rearward or lower edges of the frames 105 and serve to receive pins 114, by means of which the frames are coupled to the angle plates 115 which are carried by supports 116, which supports are secured to and rise from the floor of the car 10.

Lugs 117 are secured to the upper or forward edges of the frames 105, and these lugs have pivotal connection with the respective ends of a pair of toggle links 118, the other ends of which are pivotally connected with ears 119, extending from a toggle head 120 at diametrically opposite positions thereon. The toggle head 120 is apertured to receive with a sliding fit, the guide rods 121 the ends of which are secured in the supports 122, suitably secured to the frame-work of the tower. A threaded shaft 123 is journaled in the supports 122 and its threads engage with the interior threads of the toggle head 120. The forward end of the shaft 123 extends beyond its support 122 and a chain wheel 125 is fast on this extending end. A chain 126 is trained over the wheel by which the wheel may be manually rotated for the purpose of actuating the toggle mechanism to swing the frames 105 outwardly beside the car, when the tower is to be elevated, and inwardly upon the supports 116 when the tower is in lowered position.

Bumper standards 127 are secured to the floor of the car 10, at each side thereof, and these standards carry bumper blocks 128, which are held in a normally elevated position by the coiled compression springs 129. These bumper blocks are so positioned as to engage the frame-work of the tower, at either side thereof and toward the upper end of the tower, and support the tower when in lowered position, as seen most clearly in Fig. 1.

Plates 130 are secured at each side of the car 10 and the ends of these plates are bent outwardly and apertured to receive, with a sliding fit, rods 131, the forwardly projecting ends of which are encircled by coiled

compression springs 132, which springs are confined between the heads 133, formed on the forward end of the rods, and the forward outwardly bent ends of the plates 130.

5. These devices are so positioned as to form bumpers which contact the rear edges of the frames 105, when the tower is swung to elevated position, and so bring the tower gradually to rest.

10. When in use the device is operated in the following manner:

The tower being in the position shown in Fig. 1, the car is propelled to the desired location, the pins 114 are withdrawn to free 15 the frames 105 so that they be swung outwardly to each side of the car. The chain 126 is then drawn to rotate the wheel 125 and shaft 123 in a direction to cause the head 120 to travel forwardly. This motion 20 of the head will, through the toggle links 118, swing the frames to the desired positions.

The crank 102 is then rotated to rotate the shaft 98 which, through the worm gear, 25 shaft 93, pinions 92 and segmental racks 90, will cause the tower to swing to elevated position.

During the swing of the tower from the position of rest to that of elevation, the 30 platform 33 will, through the force of gravity, assisted by the equalizing mechanism consisting of the wheels 39 and 44 and the rope 40, remain in a position parallel with the floor of the car 10. When the 35 tower has reached its position of complete elevation the platform will have swung into the yoke at the top of the tower and the catch 53 will contact the edge 51 of the latch and cause the latch to rise until the 40 catch is in alinement with the notch 52 of the latch, when the latch will fall by gravity to engage the catch. At the time that the catch has come into alinement with the notch 52, the bumper plate 74 comes into engagement 45 with the angular projection 73 of the stop 72 and prevents further swing of the platform.

The attendant may now ascend the tower by means of the ladder and, when he has 50 arrived at the top of the ladder, he may grasp the extension ladder and draw the same downwardly until the lower ends of its side bars 83 rest against the plates 87. This movement of the ladder will, as hereinbefore explained, swing the trap-door upwardly, in which position it will be held by the counter-weight 86. The attendant may now pass up the extension ladder and through the opening to the platform 33 and 55 be in position to operate the searchlight.

To prevent lateral oscillations of the tower and the car, the jack screws are operated, through the hand wheels 110, to bring feet 111 into contact with the ground or with 60 blocks 134, placed at each side of the track.

When the tower is to be again lowered, the jack screws are raised through rotation of the hand wheels 110, the trap-door is unlatched, either through operation of the rod 55 and wing 60, or by drawing the handle 66 of the rod 65 downwardly below the lower flange of the plate 68, as hereinbefore described, which leaves the platform free to swing upon its trunnions.

The tower is then lowered by rotation of 75 the crank 102 and, as the tower starts toward the lowered position, the lower ends of the side bars 83 of the extension ladder will be drawn against the angle plates 87, causing the shaft 81 to rock, which, through the 80 cranks 82 and 78', will rock the shaft 78 and cause the trap-door 76 to close.

When the tower has reached its lowermost position, the chain 126 is drawn to revolve the wheel 125 in a direction to cause the nut 120 to move rearwardly and, through the 85 links 118, draw the frames 105 inwardly to rest upon the supports 116. The pins 114 may then be inserted in place to lock the 90 frames upon the support.

Having described my invention, what I claim as new is:

1. A railway tower, comprising in combination a support, a tower pivoted at its base to the support, and operable to horizontal and vertical positions, a platform pivoted to the upper end of the tower, means for retaining the platform in parallelism with the support for all positions of the tower, including rotatable members affixed to the pivots of the tower and platform and a connection between said members and mechanism for automatically locking the platform parallel with the support as the tower attains its maximum elevation, such means comprising a keeper projecting from the platform and a latch connecting therewith and pivoted to the support. 95 100 105

2. A railway tower, comprising in combination a support, a tower pivoted at its base to the support, and operable to horizontal and vertical positions, a platform pivoted to the upper end of the tower, means for retaining the platform in parallelism with the support for all positions of the tower, embracing interconnected rotatable members affixed to the pivots of platform and tower, mechanism for automatically locking the platform parallel with the support as the tower attains its maximum elevation, including a keeper affixed to the platform and a latch plate pivoted to the tower and adapted to engage the keeper, said plate being formed at its outer end to enable its elevation by the keeper as the platform reaches a horizontal 110 115 120 125 position.

3. A railway searchlight tower comprising in combination a support, a tower pivoted at its base to the support and operable to horizontal and vertical positions, a platform piv- 130

- oted to the upper end of the tower, means for retaining the platform in parallelism with the support for all positions of the tower, including interconnected rotatable members affixed to the pivots of the tower and platform, mechanism for automatically locking the platform parallel with the support as the tower attains its maximum elevation, including a keeper projecting from the platform and a latch plate pivoted to the support and having a seat to receive the keeper, the forward end of the plate being beveled to enable its elevation prior to seating of the keeper.
- 15 4. A railway tower, comprising in combination a transportable support, a tower pivoted at its base to the support and operable to horizontal and vertical positions, a platform pivoted in the upper end of the support, means for retaining the platform in parallelism with the support for all positions of the tower, embracing interconnected rotatable parts affixed to the pivots of the tower and platform, mechanism for automatically locking the platform parallel with the support as the tower attains its maximum elevation, including a keeper secured to the platform at its edge, a latch plate pivoted to the tower and formed with a seat to receive the keeper, the forward lower edge of the latch plate being beveled to enable elevation of the plate prior to seating of the keeper.
5. A railway tower, comprising in combination a transportable support, a tower pivoted at its base to the support and operable to horizontal and vertical positions, a platform pivoted in the upper end of the tower, means for retaining the platform in parallelism with the support for all positions of the tower, embracing interconnected rotatable members affixed to the pivots of tower and platform, a mechanism for automatically locking the platform parallel with the support as the tower attains its maximum elevation, comprising a keeper affixed to the edge of the platform and a latch plate pivoted to the tower and formed with a seat to receive the keeper, and means permitting manual operation of the latch plate from the platform embodying an operating rod connected with the latch plate and extending to a point adjacent the upper end of the tower.
6. A railway searchlight tower, comprising in combination a transportable support, a tower pivoted at its base to the support and operable to horizontal and vertical positions, a platform pivoted in the upper end of the tower, means for retaining the platform in parallelism with the support for all positions of the tower embracing interconnected rotatable members affixed to the pivots of the tower and platform, a mechanism for automatically locking the platform parallel with the support as the tower attains its maximum elevation, comprising a keeper
- its maximum elevation, including a keeper affixed to the platform and a latch plate pivoted to the tower and formed with a seat to receive the keeper and means to permit manual operation of the latch plate for either platform or support embodying operating rods connected to the extremities of the latch plate and extending to points contiguous the top and bottom of the tower.
7. A railway searchlight tower, comprising in combination a transportable support, a tower pivoted at its base to the support and operable to horizontal and vertical positions, a platform pivoted in the upper end to the tower, means for retaining the platform in parallelism with the support for all positions of the tower, embracing interconnected rotatable members affixed to the pivots of tower and platform, a mechanism for automatically locking the platform parallel with the support as the tower attains its maximum elevation, comprising a keeper carried by the platform and a latch plate pivoted to the tower, and means for effecting release of the latch plate from the platform and support comprising operating rods connecting with the extremities of the latch plate and extending to points on the tower adjacent to the top and bottom thereof.
8. A railway searchlight tower, comprising in combination a transportable support, a tower pivoted at its base to the support and operable to horizontal and vertical positions, a platform pivoted in the upper end of the support, means for retaining the platform in parallelism with the support for all positions of the tower embracing interconnected rotatable members affixed to the pivots of the tower and platform, a mechanism for automatically locking the platform parallel with the support as the tower attains its maximum elevation, comprising a keeper carried by the platform and a latch plate pivoted to the tower and formed with a seat to receive the keeper and means for effecting release of the latch plate comprising an operating rod connected to the latch plate and extending to a point contiguous the upper end of the tower, and gravity controlled means coacting with the operating rod to retain the latch plate in elevated position.
9. A railway searchlight tower, comprising in combination a transportable support, a tower pivoted at its base to the support and operable to horizontal and vertical positions, a platform pivoted in the upper end of the tower, means for retaining the platform in parallelism with the support for all positions of the tower, embracing interconnected rotatable members affixed to the pivots of the tower and platform, mechanism for automatically locking the platform parallel with the support as the tower attains its maximum elevation, comprising a keeper

- carried by the platform and a latch plate pivoted to the tower and formed with a seat to receive the keeper, means to effect manual releasement of the latch plate, comprising an operating rod connected to the latch plate and extending to a point contiguous the upper end of the tower and a retaining plate cooperating with the rod to engage the latter and retain the latch plate in elevated position, said rod being mounted for gravity releasement when the platform attains a horizontal position.
10. A railway searchlight tower, comprising in combination a support, a tower pivoted to the support and operable to horizontal and vertical positions, counterweighted frames horizontally connected at their upper extremities to the base of the tower and at opposite sides thereof, a vertically movable member mounted central of the tower and adjacent its base, connections between said member and the counter-
- weighted frames and means for actuating said member to effect lateral actuation of the frames for the purpose of supporting the tower against transverse oscillations when it is in an elevated position.
11. A railway searchlight tower comprising in combination a support, a tower pivoted at its base to the support and operable to horizontal and vertical positions, counterweighted frames horizontally connected in opposed relations to the lower end of the tower, vertical guides mounted on the tower adjacent its lower end, a toggle head slidably positioned on the guides, links connecting the toggle head with the counterweighted frames and means to vertically actuate said toggle head to place the frames in divergent relation when the tower is in elevated position, and in substantial parallelism when the tower is in its lowered position.
